UNITED STATES PATENT OFFICE.

RONAN CALISTUS GRADY, OF EAST BOSTON, MASSACHUSETTS.

FOG-LIGHT.

1,362,693.

Specification of Letters Patent. Patented Dec. 21, 1920.

Application filed February 24, 1920. Serial No. 360,719.

To all whom it may concern:

Be it known that I, RONAN CALISTUS GRADY, a citizen of the United States, and a resident of East Boston, in the county 5 of Boston and State of Massachusetts, have invented certain new and useful Improvements in Fog-Lights, of which the following is a specification.

My invention is an improvement in fog 10 lights, and has for its object to provide a light primarily designed for marine use, and when the visibility is low, as for instance during a fog or on a dark night, when the navigational lights cannot be seen, 15 wherein the light is so arranged that a powerful ray may be sent downwardly through the water at a slight angle, to be reflected from the bottom, to cause the reflected rays to be visible at the side of the ship when 20 the water is shallow.

In the drawings:—

Figure 1 is a diagrammatic view showing the arrangement of the light and the manner of its use,

Fig. 2 is a vertical section through the light,

Fig. 3 is a horizontal section at the level of the lens,

Fig. 4 is a similar view at the level of 30 the arc.

The present invention is designed to provide a light which may be used with vessels, to indicate especially shallow water, by the reflection of the light from the bottom, the light being so arranged that the rays will be directed through the water toward the bottom. With this object in view, I provide a casing consisting of an upper section 1 of substantially cylindrical 35 form, an intermediate section 2 and a lower section 3, the sections having radial flanges 4 which are connected together by bolts 5 as shown.

A head 6 is secured to the outer flange 45 4 of the section 1, and the outer flange 4' of the section 3 is designed to be secured to the bottom of the vessel 7 by means of bolts 8, the said section 3 being arranged at an opening 9 in the hull. Between the 50 flanges of the sections 1 and 2, there is arranged a ring 10, which carries a lens 11 and above the lens there is arranged an arc light in the section 1.

This arc light consists of a pencil 12 55 which is held by an insulating sleeve 13 in the wall of the section 1, and a pencil 14

which is mounted in a bearing bracket 15 on the wall at the opposite side of the section. The section 1 has an opening at the pencil 14, which is covered by a plate 16 held in place by screws 17, and the pencil 60 has a regulating knob 18 at the opening, which is accessible when the plate is removed.

Lead wires 19 supply current for the arc. 65 A reflector 20 is connected with the head 6, the reflector as shown having an axial stem which has a reduced threaded portion engaging a threaded opening in the head.

The section 2 of the casing has an enlargement 21 which forms a valve casing. 70 Within this casing there is arranged a gate or valve, by means of which communication between the upper part of the section and the lower part may be closed when the light 75 is not in use. This gate or valve is closed by a threaded stem 22 having a hand wheel as shown.

In the operation of the device, when for any reason the visibility is so low that navigation is difficult or dangerous, because of shallow water and the like, the gate will be opened, the arc light will be turned on, and a powerful beam will be reflected through the lens 11 downwardly and slightly outwardly as shown. 80

If there is shallow water, the rays will be reflected upwardly and outwardly as indicated in broken lines in Fig. 1, and these reflected rays will be visible to those 90 interested. The depth of the water may be established in this manner, and because of the fact that the reflected rays are so close to the vessel, the low visibility will not interfere with the proper seeing of the same. 95

When not in use, the gate is closed to protect the parts from the water, and it may be closed to permit the light to be overhauled. The lens prevents the water from entering the arc chamber. The distance 100 from the ship at which the reflected rays is seen, the angle of incidence being known, will permit a reasonably close establishment of the depth to be made. When the reflected rays draw nearly to the ship, it 105 will be a warning that the water is shoaling, and that soundings should be taken. By watching the reflected rays, the shoaling and deepening of the water may be seen, regardless of the conditions of visibility. 110

I claim:—

1. A device of the character specified,

adapted to be arranged at an opening in the hull of the vessel below the water line, and comprising a casing having means for connecting it to the hull at the opening, that 5 end of the casing adjacent to the opening being open, a lens supported transversely of the casing intermediate its ends and forming a water tight closure, a source of illumination arranged between the lens and the 10 upper end of the casing, a reflector above the source, and means for forming a water-tight closure transversely of the casing between the lens and the open end, said means comprising a gate moving transversely of 15 the casing, and means for controlling the gate.

2. A device of the character specified, adapted to be arranged at an opening in the hull of the vessel below the water line 20 and comprising a casing having means for connecting it to the hull at the opening, that end of the casing adjacent to the opening being open, a lens supported transversely of the casing intermediate its ends 25 and forming a water-tight closure, a source of illumination arranged between the lens and the upper end of the casing, the source of illumination comprising an arc light having an electrode fixedly supported by the 30 casing wall, and an electrode movably supported by the wall at the opposite side and movable toward and from the first electrode, the casing having an opening at the last

named electrode and a cover plate for the same. 35

3. A device of the character specified, adapted to be arranged at an opening in the hull of a vessel below the water line, and comprising a casing having means for connecting it to the hull at the opening, that 40 end of the casing adjacent to the hull being open and the other end being closed, a lens supported transversely of the casing intermediate the ends thereof and forming a water-tight closure, a source of illumination 45 between the lens and the closed end of the casing, and a gate movable transversely of the casing between the lens and the open end, and forming a water-tight closure when closed. 50

4. A device of the character specified, adapted to be arranged at an opening in the hull of a vessel below the water line, and comprising a casing having means for connecting it to the hull at the opening, that 55 end of the casing adjacent to the hull being open and the other end being closed, a lens supported transversely of the casing intermediate the ends thereof and forming a water-tight closure, a source of illumination 60 between the lens and the closed end of the casing, and means movable transversely of the casing between the lens and the open end for forming a water-tight closure.

RONAN CALISTUS GRADY.
